Primary Examiner — Randall Gholson*(74) Attorney, Agent, or Firm* — Lawrence G. Fridman, Esq.(57) **CLAIM**

The ornamental design for a torque wrench, as shown and described.

DESCRIPTION

FIG. 1 is a perspective view of the torque wrench according to my new design;

FIG. 2 is a bottom view thereof; and,

FIG. 3 is a side view thereof.

The broken lines depict portions of the torque wrench that form no part of the claimed design.
